UNITED STATES PATENT OFFICE.

MILO P. SMITH, OF NORWALK, OHIO.

SEWING-MACHINE.

SPECIFICATION forming part of Letters Patent No. 280,409, dated July 3, 1883.

Application filed March 20, 1883. (No model.)

To all whom it may concern:

Be it known that I, MILO P. SMITH, of Norwalk, in the county of Huron and State of Ohio, have invented certain new and useful Improvements in Sewing-Machines; and I do hereby declare the following to be a full, clear, and exact description of the invention, such as will enable others skilled in the art to which it app pertains to make and use the same.

10 My invention relates to an improvement in sewing-machines, the object of the same being to provide simple, durable, and efficient feed-operating mechanism, and improved means for changing the length of stitch; and with 15 these ends in view my invention consists in the parts and combinations of parts, as will be more fully described, and pointed out in the claims.

In the accompanying drawings, Figure 1 is 20 a view in side elevation and partly in section of my improved machine. Fig. 2 is a bottom plan view of the same. Fig. 3 is an end view. Fig. 4 shows detached views of the shuttle-lever and feed-operating lever, and Fig. 5 an 25 elevation of one of the operating-cams.

A represents a bed-plate provided with the upwardly-extending hollow arm B, through the upper end of which latter the drive-shaft C passes. This shaft C is driven in the ordinary manner, and is provided near its rear end, inside of the arm B, with the two cams D D', which latter operate, respectively, the 30 vibrating levers E E'. These levers are pivotally secured within the arm B to the shaft F, and are bifurcated or forked at their upper 35 ends to partly embrace the cams D D' on the driving-shaft C, through which motion is imparted thereto. The lever E is situated in front of the lever E', and the lower end thereof 40 is provided with a circular head, a, which latter rests in the bifurcated rear end of the shuttle-lever H, and operates the same in the ordinary manner. This shuttle-lever is pivotally 45 secured to the lower face of the base-plate, and is provided at its front end with a shuttle-carrier, b, within which the removable shuttle is located. The shuttle-lever is pivoted to one 50 side of its center, near its rear bifurcated end, and is provided at one side, immediately opposite its pivotal point or axis, with the laterally-projecting arm I, which latter is preferably cast in the same piece with the shuttle-lever.

The outer end of the arm I is connected to the link J through the intervention of the pivot-pin e, while the rear end of the said link is 55 pivotally secured to the upper face of the operating-lever K. From the foregoing it will be seen that when the shuttle-lever is operated the feed-operating lever K is also moved backward and forward simultaneously with 60 the movement of the said shuttle-lever, thereby imparting to it two movements, while the mechanism hereinafter to be described gives it the necessary lateral movements.

L is a sliding bar adapted to be moved in the 65 guides f. This bar is provided on its lower face, at its front end, with an inwardly-projecting finger, g, the end of which latter is adapted to receive and support the pivotal bearing-block M, while the front end of the said bar is 70 provided with an upwardly-projecting screw, N, having a female screw-threaded cap, O, by means of which the bar is held in position. The bearing-block M is grooved on its upper face for the passage of the feed-operating lever, 75 and forms a pivot for the said lever. By moving the sliding bar L backward the bearing-block M is also moved in the same direction, which brings the fulcrum of the lever K nearer the center, thereby increasing the lateral play 80 of the forward end of the said lever, and consequently increasing the length of the stitch. When it is desired to shorten the stitch, the sliding bar is moved forward, so as to bring the fulcrum of this feed-operating lever K 85 nearer its outer end, which limits the lateral play of the front end of the said lever, thereby shortening the stitch. The front end of the feed-operating lever K is provided with an inclined upper face, and passes through an 90 open slot in the spring-actuated feed-bar P, and imparts thereto lateral movement in both directions and an upward movement while the said feed-bar is feeding the fabric forward, while the rear curved end of the said lever 95 terminates in a horizontal finger, i, which latter passes through and moves in a circular bearing formed in the lower end of the vibrating lever E'. This finger is free to be moved longitudinally through the bearing in the lower 100 end of the lever E' as the feed-operating lever is moved forward and backward by the shuttle-lever K.

Motion is imparted to the drive-shaft in the

ordinary manner, which in turn vibrates the levers E and E' simultaneously in opposite directions. The lever E', being connected by a sliding joint to the feed-operating lever, im-
 5 parts to the said lever the necessary lateral motions, while the shuttle-lever, which is also connected therewith by a link, gives it the necessary longitudinal movements.
 The cam D' on the shaft C is so shaped and
 10 secured relatively to the said shaft as to vi-
 brate the lever E' from right to left with a
 short stoppage between each movement, while
 the cam D is circular and secured eccentric-
 ally to the shaft, and consequently moves the
 15 shuttle-lever from right to left without inter-
 mission. Thus it will be seen that when the
 cam D' on the driving-shaft has moved the
 lower end of the vibrating lever E in one di-
 20 rection the latter, through the intervention of
 the feed-operating lever, moves the feed-bar
 backward. The vibrating lever thus remains
 stationary for a short interval, during which
 time the shuttle-lever moves the feed-operat-
 25 ing lever forward. After the last movement
 the lower end of the vibrating lever is moved
 in the opposite direction and again comes to
 rest, and the shuttle-lever draws the feed-op-
 erating lever backward, during which move-
 30 ment the teeth of the feeder-bar are brought
 up flush with the upper surface of the base-
 plate by means of the inclined or wedge-shaped
 face of the feed-operating lever. The next
 movement of the vibrating lever E' moves the
 35 feeding-bar forward, and so on continuously.
 This machine is exceedingly simple in con-
 struction, is not liable to get out of repairs,
 and can be manufactured and sold at a com-
 paratively small initial cost.
 It is evident that slight changes in the con-
 40 struction and relative arrangement of the sev-
 eral parts might be resorted to without de-
 parting from the spirit of my invention; and
 hence I would have it understood that I do not

limit myself to the exact construction shown and described, but consider myself at liberty 45 to make such alterations as fairly fall within the spirit and scope of my invention.

I would not have it understood that I am intending to claim, broadly, the combination of the shuttle-lever connected to a feed-oper- 50 ating lever provided with an adjustable piv-
 oital point, by which connection and adjusta-
 ble point it receives a longitudinally-recipro-
 cating motion, as well as a variable vibratory
 motion, since the same is, to my knowledge, 55 in this broad sense, not new.

Having fully described my invention, what I claim as new, and desire to secure by Letters Patent, is—

1. The combination, with a shuttle-lever, 60 having a laterally-extending arm and a link pivoted thereto, of a feed-operating lever con-
 nected by means of the said link to the arm, and the vibrating lever connected to the rear end of the feed-operating lever by an adjusta- 65 ble sliding bearing fitting over a projecting finger, a sliding bar provided with a pivoted fulcrum for the feed-operating lever, and a screw for adjustably holding the bar in position, substantially as shown and described. 70

2. The combination, with the driving-shaft, provided with cams, and the vibrating levers, of the shuttle-lever provided with the laterally-extending arm and the link attached there-
 to, the feed-operating lever connected to said 75 arm by a link, and the sliding bar and move-
 able fulcrum, all of the above parts combined and constructed substantially as described.

In testimony whereof I have signed this specification in the presence of two subscrib- 80 ing witnesses.

MILO P. SMITH.
